CHARLES F. SULTEMEYER, OF OAK PARK, ILLINOIS, ASSIGNOR TO CHICAGO MANUFACTURING AND DISTRIBUTING CO., A CORPORATION OF ILLINOIS.

FORGING-DIE.

1,355,434.

Specification of Letters Patent. Patented Oct. 12, 1920.

Application filed June 23, 1919. Serial No. 306,058.

To all whom it may concern:

Be it known that I, CHARLES F. SULTEMEYER, a citizen of the United States, and resident of Oak Park, county of Cook, and 5 State of Illinois, have invented certain new and useful Improvements in Forging-Dies, of which the following is a specification, and which are illustrated in the accompanying drawings, forming a part thereof.

10 The invention relates to dies for forging annular machine parts and the like from a solid bar without waste of material. While annular forgings have heretofore been produced by first upsetting an end portion of a 15 solid bar and then punching longitudinally through the resulting enlargement or head whereby the part removed is retained as an integral part of the original bar and there is no loss of material in the forging opera- 20 tion, it has not been possible to obtain such accuracy in the production of these forgings as would permit of their use as machine parts without subsequent finishing embodying the removal of considerable amounts of 25 material with cutting tools. Furthermore, the forgings produced by this method, as heretofore practised, have not been adapted for hardening by heat treatment without other preparatory operations.

30 The present invention accordingly has for its object the provision of improved dies designed to secure the greatest accuracy in the formation of annular forgings from a solid bar with the proper working of the 35 metal for obtaining the requisite density and strength to permit the forgings to withstand subsequent hardening by heat treatment and severe service in use.

In the accompanying drawings:—

40 Figure 1 is a side elevation showing one of a pair of die blocks embodying the features of improvement provided by the invention, together with the associated punches and a bar of stock upon which one step of 45 the forging operation has been performed, the said bar of stock being partly in section,

Fig. 2 is similar to Fig. 1, but shows the punches fully entered in the die block with the completed forging, in section, resting in 50 the corresponding die and the bar of stock in advance of the punch,

Fig. 3 is a perspective view of the completed forging, partly in section,

Fig. 4 is a detail plan view of a forging press with the improved dies mounted therein, the die blocks being closed upon a bar of stock and the punches fully entered, and 55

Fig. 5 is a detail end elevation of the forging press with the die blocks in open or separated position. 60

The particular apparatus selected for the purpose of illustrating the invention is designed for forging roller bearing races of the form shown at 10 in Fig. 3 from a solid round bar, as 11, (Figs. 1 and 2). This 65 roller bearing race has a beveled interior surface 12, a bulging exterior surface 13, and flattened ends 14 and 15. In the use of the improved dies, it is proposed that machine parts, as for example, the said roller 70 bearing race 10, are to be produced from high carbon steel or steel alloy and so accurately forged that no machine work with cutting tools will be required to be done upon them, but only such grinding as may 75 be necessary to remove fins and the like, smooth the edges, as 14, 15, and polish the wearing surface 12. Under these circumstances, no carbonization or case hardening is required, but machine parts of superior 80 quality will be produced if the forgings are merely quenched in oil from a temperature above decalescence for the particular steel or steel alloy employed.

The original bar, as 11, may accordingly 85 be of chrome steel, preferably containing .90 and 1.00 per cent. carbon and between 1.25 and 1.40 per cent. chromium, and the size of the bar is desirably about the same as the smallest interior diameter of the completed 90 forging. When such a bar is used it is heated to a forging temperature at one end and each forging operation is performed in steps by two dies 16, 17, and the corresponding punches 18, 19. 95

To permit the insertion of the bar, as 11, and its transfer from one to the other of the dies 16, 17, each of said dies is formed in two like halves and a pair of relatively movable die blocks 20, 21, are provided, each of the said die blocks serving to carry one part of both dies. As shown, the separate parts

of the dies 16, 17, are each set into the corresponding die blocks 20, 21, and permanently secured therein. To prevent relative displacement of the two parts of the dies 5 when closed upon the work, the two die blocks 20, 21, are preferably formed with an intercolating rib 22 and groove 23 extending across the meeting faces of the same.

In practice, the two die blocks 20 and 21 10 may be mounted in a forging press of well known construction comprising movable and fixed jaws 24 and 25 and a reciprocating plunger 26, the latter serving to carry the punches 18 and 19. When so mounted die blocks 20, 21, have relative movement to 15 open and close the two parts of the dies 16, 17, upon the work and the punches 18, 19 move longitudinally into the said dies when closed. As the said dies and punches are 20 operable upon only an end portion of the bar, as 11, the die blocks 20 and 21 are each grooved in alinement with the corresponding die parts, as at 27 and 28, to receive the bar, the grooves 27, in alinement 25 with die 16 being shallower than the grooves 28, in alinement with die 17, to permit the bar, as 11, being firmly gripped between the die blocks 20, 21, and securely held thereby during the operation of punch 30 18 and die 16, while allowing the bar 11 to be moved between the die blocks 20, 21, by the advancing plunger 19.

As shown, die 16 is formed to provide 35 a socket 29 having a rounded inner end 30 and the corresponding punch 18 is formed with a rounded head 31. The operation of punch 18 and die 16 is therefore to upset the heated end of the firmly held bar, as 11, leaving the same with an enlarged head 40 32, having a cupped end 33. As the bar 11 is to be firmly held between the die blocks 20 and 21 during this operation it is, of course, important that the bar shall be heated to a forging temperature only in the portion 45 immediately adjacent its end for the part of the bar in rear of the die 16 must be sufficiently cold to resist the gripping action of the die blocks.

After the end portion of the bar has been 50 upset by the coaction of the die 16 and punch 18 to form the enlarged head 32, the die blocks 20, 21, are separated by lateral movement of the die block 20. While so separated the bar 11 is transferred to the 55 position illustrated in Fig. 1 wherein the enlarged head 32 is seated in the die 17 and the adjacent portion of the bar rests in the groove or channel 28. The die blocks 20, 21, are then closed upon the bar and the 60 plunger 26 is again advanced to enter the punches 18, 19, in the corresponding dies. During this part of the operation, the movement of punch 18 into die 16 is idle, but the 65 operation of punch 19 has to first pierce the enlarged head 32, then expand the ring so

formed against the side walls of die 17, and finally compress the ring in the direction of the axis of the punch and die. For this purpose the punch 19 is formed with a cylindrical forward portion 34, a tapering 70 intermediate portion 35 and an abutment shoulder 36, located immediately beyond the tapering portion 35. As shown, the cylindrical forward end portion 34 of the punch 19 is of the same size as the bar 11. 75 In piercing the enlarged head 32, it accordingly forces the bar backwardly in the channel 28, the part removed from the central portion of the enlarged head 32 being retained as an integral part of the bar. 80

Die 17, like die 16, is formed to provide a socket 37 and in each of these dies the side wall of the corresponding socket, 29 or 37, is cylindrical for a substantial distance adjacent the mouth of the socket. In die 85 17, however, the side wall of the socket is undercut adjacent the inner end of the socket thereby providing an annular rounded channel 38 which conforms in shape with the bulging exterior surface of the machine 90 part 10 and into which the material is expanded by the tapering intermediate portion 35 of the punch 19. After this expansion of the material it is compressed by the engagement therewith of the shoulder 36, 95 thereby insuring the accurate conformation of the interior and exterior surfaces of the finished forging with the tapering intermediate portion 35 of the punch and the rounded undercut portion 38 of the die respectively. The compression of the material by the shoulder 36 is also important for imparting the density of structure required in the machine part when it is to be hardened by heat treatment. 100

Preferably both of the punches 18 and 105 19 are formed with cylindrical body portions, as 39 and 40, which enter and closely fit the cylindrical portions of corresponding die sockets 29 and 37. As shown, each of 110 the die sockets 29 and 37 are of such depth that the cylindrical body portions 39, 40, of the corresponding punch has a substantial engagement with the side wall of the die socket during the compression of the material between the co-operating punch and die members. Accurate centering of each punch in the corresponding die is thereby insured and uniform thickness of material throughout the circumference of the finished machine part is obtained. 115

During withdrawal of the punch 19, the completed forging is retained within the die 17 by its engagement with the undercut side wall of the die and the forging is thus 120 stripped from the cylindrical forward end portion 34 of the punch. As soon as the punch has become disengaged from the completed forging the latter is removed from the die 17 by separation of the die blocks 125 130

20 and 21. The mechanism for operating the plunger 26, carrying the punches 18, 19, and for moving the jaw 24, carrying die block 20, forms no part of the present 5 invention and being of well known construction in forging machines now in use, is not illustrated in the drawing. The close fitting of the rib 22 on die block 20 in the groove 10 23 of die block 21 is of importance for maintaining accurate register of the two parts of the dies, particularly during compression of the forging in die 17 by the engagement therewith of the shoulder 36 on punch 19.

15 I claim as my invention:

1. A forging apparatus comprising, in combination, a socketed die block having a central opening of less diameter than the 20 socket extending through the same from the floor of the socket, the side wall of the socket being cylindrical for a substantial distance adjacent the mouth of the socket, and a punch having a cylindrical body portion closely fitting the said cylindrical portion 25 of the die block socket and a forming head of a size not exceeding the diameter of the cylindrical body portion located in advance of the said body portion.

2. A forging apparatus comprising, in combination, a socketed die block having a central opening of less diameter than the 30 socket extending through the same from the floor of the socket, the side wall of the socket being cylindrical for a substantial distance adjacent the mouth of the socket and undercut adjacent the floor of the socket, and a punch having a cylindrical body portion closely fitting the cylindrical portion 35 of the die block socket, a cylindrical piercing projection at its forward end fitting the die block opening and a tapering intermediate portion extending between the said piercing projection and the body portion.

3. A forging apparatus comprising, in combination, a socketed die block having a central opening of less diameter than the 45 socket extending through the same from the floor of the socket, the side wall of the socket being cylindrical for a substantial distance adjacent the mouth of the socket and undercut adjacent the floor of the socket, and a punch having a cylindrical body portion closely fitting the cylindrical portion of the die block socket, a cylindrical piercing projection at its forward end fitting the die 50 block opening and a tapering intermediate portion extending between the said piercing projection and the body portion, the largest diameter of the tapering intermediate portion of the punch being less than the diameter of its said cylindrical body portion whereby a forwardly facing annular abutment shoulder is provided at the forward 55 end of the said body portion.

4. A forging apparatus comprising, in combination, a socketed die block having a central opening of less diameter than the 60 socket extending through the same from the floor of the socket, the side wall of the socket being cylindrical for a substantial distance 70 adjacent the mouth of the socket, and a punch having a cylindrical body portion closely fitting the said cylindrical portion of the die block socket, a cylindrical piercing projection at its forward end fitting the 75 die block opening and a forwardly facing annular abutment shoulder at the advance end of the said cylindrical body portion, and a forming head of a size not exceeding the diameter of the cylindrical body portion 80 located in advance of the said body portion.

5. A forging apparatus comprising, in combination, a longitudinally divided socketed die block having a central opening of less diameter than the socket extending 85 through the same from the floor of the socket, the side wall of the socket being cylindrical for a substantial distance adjacent the mouth of the socket and the named parts of the die block being each partially 90 formed in the different divisions of the block, and a punch having a cylindrical body portion closely fitting the said cylindrical portion of the die block socket and a forming head of a size not exceeding the 95 diameter of the cylindrical body portion located in advance of the said body portion.

6. A forging apparatus comprising, in combination, a longitudinally divided socketed die block having a central opening of 100 less diameter than the socket extending through the same from the floor of the socket, the side wall of the socket being cylindrical for a substantial distance adjacent the mouth of the socket and undercut adjacent the floor of the socket, the named parts of the die block being each partially formed in the different divisions of the block, and a punch having a cylindrical body portion closely fitting the cylindrical portion of the 110 die block socket, a cylindrical piercing projection at its forward end fitting the die block opening and a tapering intermediate portion extending between the said piercing projection and the body portion. 115

7. A forging apparatus comprising, in combination, a longitudinally divided socketed die block, the plane of division of the block extending centrally through its socket and the meeting faces of the parts of the 120 die block being formed with a transverse intercolating tongue and groove, and a punch entering the die block socket.

8. A forging apparatus comprising, in combination, a longitudinally divided socketed die block having an opening extending longitudinally through the same from the floor of the socket, the plane of division of 125

the block extending centrally through its socket and opening and the meeting faces of the parts of the die block being formed with a transverse intercalating tongue and groove, and a punch entering the die block socket.

9. A forging apparatus comprising, in

combination, a longitudinally divided socketed die block, the plane of division of the block extending through the die socket, intercalating projections and sockets on the meeting faces of the parts of the die block and a punch entering the die socket. 10

CHARLES F. SULTEMEYER.
